Attorneys.

UNITED STATES PATENT OFFICE.

JEAN PÉRONY, OF ST.-OGEN, FRANCE, ASSIGNOR TO SOCIETE D'OUTILLAGE
MÉCANIQUE ET D'USINAGE D'ARTILLERIE, OF ST.-OGEN, FRANCE, A JOINT-
STOCK COMPANY OF FRANCE.

COVER FOR DIGESTERS AND OTHER APPARATUS.

1,371,393.

Specification of Letters Patent.

Patented Mar. 15, 1921.

Application filed February 24, 1920. Serial No. 360,794.

To all whom it may concern:

Be it known that I, JEAN PÉRONY, a citizen of the Republic of France resident of 19 Avenue de la Gare, St.-Ouen, Seine, France, have invented new and useful Improvements in Covers for Digesters and other Apparatus, which is fully set forth in the following specification.

In a great number of machines, as for example in digester presses for vulcanizing rubber, it is necessary to be able to close and open rapidly a vessel subjected to internal pressure.

In certain cases, the action of the internal pressure upon the joint packing of the cover renders the removal of this cover very difficult owing to the jamming of the joint packing.

The present invention has for its object an improved construction of cover in which this drawback is avoided, the removal of the cover as well as its replacement into position being capable of being effected with the greatest facility.

According to this invention, the cover comprises a packing ring of suitable plastic material mounted inside the cover and capable of being moved relatively to the latter by means of mechanism operable from the outside. By this means, without touching the cover which is in position on the vessel, it is possible to move at will the joint packing away from the body of the vessel, that is to say, to loosen it by operating the said mechanism in the requisite direction or to tighten the packing by an operation in the reverse direction.

In practice, the movable packing ring can be carried by a metal ring whose movements for the purpose of bringing the joint packing proper nearer to or away from the body of the vessel, are produced by means of a mechanism which comprises of course a member extending through the cover with a tight joint.

A practical constructional form of this invention is illustrated by way of example in the accompanying drawings showing the invention applied for jointing the cover of a bell-shaped vulcanizing press.

Figure 1 is a vertical longitudinal section along the axis of the apparatus showing the cover in position and the joint packing tightened.

Fig. 2 is a similar section showing the 55 cover in position with the joint packing loosened.

In these figures, A is the vessel adapted to receive a cover B by means of a bayonet joint or any other known means of connection. The cover has a cylindrical wall, the edge of which is adapted to engage the seat formed on the mouth of the vessel.

According to this invention, the cover is provided with a packing of plastic material 65 C which when mounted inside the said cover, can be moved relatively to the latter by means of a mechanism operable from the outside. For this purpose the packing C may be carried by a metal ring D, whose external diameter is equal to the internal diameter of the cover, and being thus guided, the mechanism which is operable from the outside allows of raising or lowering at will the said ring D, and thereby bringing the 70 lip c of the packing C into or out of contact with the mouth of the vessel A.

In the example shown, the operating mechanism consists of rocking levers E—E¹ fulcrumed on pivot pins f mounted in 80 blocks F fixed to or formed on the inner wall of the cover B. The arm E of each lever engages by means of a spherical knob e formed on its free end, in a buttonhole slot d provided in the metal ring D. The other 85 arm E¹ engages by means of a slot e¹ formed in its free end with a pin g mounted in a block G projecting from a nut H.

In this nut there is adapted to rotate the screw-threaded portion i of a spindle I 90 which is journaled with a tight joint and by means of a collar i¹ in the cover B. A hand-wheel J fixed on the spindle I, enables the spindle I to be rotated in the requisite direction, and thus cause at will the nut H to 95 move up or down along the screw-threaded portion i of this spindle. This up or down movement produces as will be seen, a corresponding downward or upward movement respectively of the ring D of the packing C 100 carried by the latter.

When it is desired to place the cover into or out of position, the packing C is brought into the position shown in Fig. 2, in which position there is no longer any contact between the said packing and its seat. From this moment onward it is easy to impart to the cover any desired movement for plac-

ing it into position upon or removing it from the vessel.

When the cover is in place, the packing is brought into the position shown in Fig. 5 1, and then immediately pressure is established in the interior of the vessel, this pressure will press the packing firmly upon its seat.

It is to be understood that the operating 10 mechanism, as also the mode of construction of the support for the joint packing proper, can vary widely in practice.

Having now particularly described and 15 ascertained the nature of my said invention and in what manner the same is to be performed, I declare that what I claim is:—

1. A tight-jointed cover for digesters and other apparatus, comprising a receptacle provided with a seat, a cover adapted to engage 20 said seat to close the receptacle, means for holding the cover in place on the seat, an element slidably mounted in the cover to move to and from the seat, a packing carried by the slidable element to be moved 25 to and from the seat, levers pivoted within the cover and engaging the slidable element, and an element connected with the levers and extending through the cover to be operated outside of the closed receptacle to move 30 the levers to actuate the slidable element carrying the packing.

2. A cover as claimed in claim 1, wherein the movable packing is carried by a metal ring fitting inside the cover and adapted 35 to receive a rising or falling movement by means of rocking levers fulcrumed on the cover and pivoted at one end to the said ring and at their other end to a nut operated by the screw-threaded portion of a spindle 40 journaled in the back of the cover.

3. A tight-jointed cover for digesters and other apparatus, comprising a receptacle provided with a seat, a cover having a cylindrical wall to engage at its edge the seat to close the receptacle, means for holding 45 the cover in place on the seat, a ring having a sliding engagement with the inner face of the cylindrical wall of the cover, a packing carried by the ring to be moved to and from the seat, levers pivoted within the 50 cover and engaging at one end the ring so that the movement of the levers will move the ring and packing to and from the seat, and an actuating member connected with the other end of the levers and extending 55 through the cover to be operated outside of the closed receptacle to move the levers.

4. A tight-jointed cover for digesters and other apparatus, comprising a receptacle provided with a seat, a cover adapted to engage 60 said seat to close the receptacle, means for holding the cover in place on the seat, a ring slidably in the cover to and from the seat, a packing carried by the ring, levers pivoted to the inner side of the cover with 65 the outer end of each lever engaging the ring, a nut engaging the inner ends of the levers, a rod journaled in the cover and extending through the same, said rod having at its inner end a threaded engagement with the nut, and turning means on the outer end of the rod for rotating said rod to raise and lower the nut to actuate the levers to slide the ring to move the packing into and out of engagement with the 70 seat.

Dated this 16th day of January, 1920.

In testimony whereof I have signed this specification.

JEAN PÉRONY.
